Patent Office, Washington, D. C.,
July 1, 1903.

Mr. Secretary of State,
Washington, D. C.

Dear Sir:

I have the honor to acknowledge the receipt of your letter of the 27th instant, and to inform you that the Patent Office has been directed to make a search for any patent or application for a patent which may have been filed in this office prior to the date of the application for the patent in question, and to furnish you with a copy of the same.

Very truly yours,

John L. Baird,
Commissioner of Patents.

UNITED STATES PATENT OFFICE

2,349,793

John N. Stewart, Detroit, Mich.

Application September 7, 1943, Serial No. 501,477

2 Claims. (Cl. 125—11)

This invention relates to a tool for dressing and truing a grinding wheel or similar device, and has for the primary object the provision of a device for the stated character which is in the form of an attachment readily adaptable to most any type of grinding machine which is provided with opposed work centering elements employing the latter for the pivotal mounting of the device on the machine and may be easily and quickly adjusted to bring the cutter thereof into a selected angle with respect to the work and also makes provision for the adjustment of the cutter relative to the work as the dressing operation progresses.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a top plan view illustrating a dressing tool constructed in accordance with my invention.

Figure 2 is a side elevation, partly in section, illustrating the device.

Figure 3 is a transverse sectional view showing the device.

Referring in detail to the drawing, the numeral 5 indicates a mounting of substantially U shape including an elongated connecting portion 6 provided with right angularly disposed end portions 7, the outer faces of which are provided with sockets 8 to receive opposed centering elements 9 of a grinding machine of most any type and not shown. The centering elements received within the sockets 8 permit the mounting to readily pivot on said centering elements. The connecting portion 6 is increased in width, as shown at 10, and has scale markings 11 arranged thereon for coaction with scale markings 12 formed on a base 13 of a tool holder 14. The base 13 is shaped similarly to the enlarged portion 10 of the mounting and is adapted to rotate thereon. The holder 14, which forms an integral part of the base 13, is of substantially rectangular shape and has formed therein a recess closed by a removable plate 15.

A pivot pin 16 threads into the base and a portion of the holder 14 and is adapted to extend freely through an opening provided in the mounting 5, and has threaded thereon a knurled nut 17.

The tightening of the nut 17 on the stem 16 will secure the base 13 of the holder 14 in any of its adjusted positions on the mounting.

Slidably received within the recess of the holder 14 is a bar 18 forming a tool holder, one end of which is provided with an opening to receive the shank 19 of a cutter 20. The cutter may be of the diamond type and is disposed laterally of one of the side faces of the holder and the other end of the latter is equipped with a handle 21 to permit the operator to impart sliding movement to the holder in either direction for the purpose of adjusting the cutter with respect to the work as the dressing operation progresses.

15 A stem 22 is threaded in the enlarged portion
10 of the mounting 5 and depends therefrom and
has threaded thereon a knurled sleeve 23 adapted
to be brought into contact with a bed or sup-
porting surface of the grinding machine for the
20 purpose of adjusting the inclination of the
mounting 5, it being understood that the mount-
ing pivots on the centering elements 9 of the
grinding machine. This will permit the cutter
element to be raised and lowered with respect to
25 the work and to adjust the cutter element to-
ward and from the work and at a selected angle,
the nut 17 is released and the base 13 is turned
on the mounting, the operator noting the scale
markings on the base as well as on the mount-
30 ing in making this adjustment so that the cut-
ter element will be arranged at a selected angle
with respect to the work. As the dressing oper-
ation proceeds, the operator may slide the tool
holder 18 in the tool holder 14 for advancing
35 the cutter as rapidly as desired during the dress-
ing operation.

Thus it will be seen that a very compact, simple and durable tool has been provided which may be easily mounted on the centering elements of most any grinding machine and will permit accurate dressing operations to be carried out on the work with a minimum expenditure of manual effort and that the cutter element may be easily and quickly brought into a selected angle with respect to the work.

50 While I have shown and described the preferred embodiment of my invention, it will be understood that minor changes in construction, combination and arrangement of parts may be made without departing from the spirit and scope of the invention as claimed.

Having thus described my invention, what I claim is:

1. In a dressing tool, a pivotally supported
55 mounting, a tool holder rotatably attached to

the mounting, a tool slidably supported by said holder, said holder and mounting having coacting scale markings thereon, and an adjustable means between the support of said mounting and the latter for adjustably restraining the pivotal movement of the mounting.

2. In a dressing tool, a substantially U shaped mounting including a connecting portion and right angularly disposed end portions provided with recesses to receive centering elements of a grinding machine, said connecting portion having a scale thereon, a base having a scale coacting with the first-named scale and rotatably se-

cured on the connecting portion and including means for releasably securing the base for rotation, a holder forming an integral part of the base, a tool rod slidably mounted in said holder and including a cutting tool at one end and a handle at the other end, a pin secured to the connecting portion of the mounting and depending therefrom, and a sleeve threaded on said pin to contact a bed of the grinding machine for adjustably restraining the pivotal movement of the mounting on the centering elements.

JOHN N. STEWART.
